The FIGURE is a top perspective view of a box for Christmas decorations embodying my new design.

The side and end not shown in the figure are substantially the same as the side and end shown. The bottom is plain.

The characteristic features of my design reside in the surface ornamentation on the top of the box in combination with the arrangement of display windows thereon, as shown, the broken line showings of light bulbs being for illustrative purposes only.

I claim:

The ornamental design for a box for Christmas decorations as shown and described.
